UNITED STATES PATENT OFFICE.

ALADAR HOLLANDER, OF BERKELEY, CALIFORNIA.

MULTISTAGE CENTRIFUGAL PUMP.

Application filed March 27, 1924. Serial No. 702,242.

To all whom it may concern:

Be it known that I, ALADAR HOLLANDER, a citizen of the United States, and resident of the city of Berkeley, county of Alameda, State of California, have invented new and useful Improvements in Multistage Centrifugal Pumps, of which the following is a specification.

The object of my invention is the arrangement of parts and passages in a multi-stage centrifugal pump whereby the several parts may be readily assembled or dismantled with the greatest ease, and whereby the machine operations are simplified and cheapened and the operation and maintenance conditions improved.

Other objects will appear from the drawings and specifications which follow.

These objects I accomplish by arranging a plurality of impellers so that their suction inlets are right and left respectively and interposing between the said impellers a diaphragm member of greater diameter than the impeller which it encloses.

This diaphragm is of circular shape and adapted to be bolted or otherwise suitably fastened within a circular opening in the casing and between the impellers thus dividing the pressure stages of the pump. Opposite the outside of one of the impellers and preferably on the high pressure side I introduce a cover adapted to close another opening in the casing large enough to pass freely the diaphragm and the impellers.

The impellers are fixed together by screw threads and are secured to the driving shaft by spline or key let into the shaft and having a head or upset portion which is clamped between the two impellers when they are screwed together. In this way the impellers are held firmly from slipping in any direction on the shaft, and upon removing one side of the pump case the impellers and the shaft may be readily removed without disturbing the discharge and suction connection to the casing.

By referring to the accompanying drawings and specifications my invention will be made clear.

Fig. 1 is a cross section through a two stage centrifugal pump in which my invention has been incorporated.

Fig. 2 is an end view of the pump in Fig. 1.

Fig. 3 is a view taken from the other end 55 of the pump in Fig. 1.

Throughout the figures similar numerals refer to identical parts.

A suction inlet of the pump is shown by the numeral 1, from which the water is taken up by the impeller 2 and discharged into the low pressure volute passage 3, from which it is delivered through the annular channel in the cover 4, to the impeller 5. The impeller 5 in turn discharges high pressure water into the volute 6 and the water passes thence through the discharge outlet 7.

At 8 is a diaphragm or disc separating the compartments of different pressure and filling an opening in the casing. Through this opening impeller 2 may be withdrawn carrying with it the shaft 9, and impeller 5. This is best accomplished by removing the cover 4 and the screws 14 releasing the diaphragm 8 which comes out with the rotating element and without disturbing the casing or any of the pipe connections.

The runners are attached to the shaft as follows:

At 20 is shown a key having a gib head 22 let into the shaft and engaging a keyway in the hub of the impeller 2. The hub is also recessed preferably by an annular cut 21 to admit the head of the key.

At 23 I show screw threads on the hub of the said impeller 2 with which corresponding threads on the hub of impeller 5 are adapted to engage.

It is of course important that the direction of rotation of the shaft 9 be such that the threads will tighten due to the torque under the operating conditions. When the impellers are tightened together the hub of impeller 5 bears against the gib head 22 thus binding the two impellers in axial relation to each other and to the shaft at the same time that the key provides the desired lock between the shaft and the impellers.

In dismantling the unit, if it is desired to remove the impellers from the shaft the cover 4 is first removed after which the impeller 5 may be removed before the diaphragm plate 8 is taken out or it may be left in place on the shaft, and then the shaft with its assembled impellers may be thereafter removed.

It will now be seen that the rotating parts

may be removed without disturbing the inlet or outlet connections 1 and 7 of the casing or disturbing the casing, full access to the interior being attained by employing 5 my invention.

I claim:

1. In a multi-stage centrifugal pump having high and low pressure impellers arranged back to back on a rotatable shaft, 10 a casing having an inlet on one side and a discharge outlet on the other side, a cover forming with said casing an intermediate passage, said casing and cover joined on a plane at right angles to said shaft and a 15 diaphragm adapted to close an opening in the casing of greater diameter than the impellers and interposed between the impellers and having a running joint with the rotatable parts therebetween, the impellers 20 being coupled by screw threads on their hubs and a spline on said shaft engaging one impeller hub and abutting against the other impeller when the runners are screwed together.
2. In a multi-stage centrifugal pump having high and low pressure impellers arranged back to back on a rotatable shaft, a casing having an inlet on one side and a discharge outlet on the other side, a cover 30 forming with said casing an intermediate passage, said casing and cover joined on a plane at right angles to said shaft and a diaphragm adapted to close an opening in the casing of greater diameter than the impellers and interposed between the impellers 35 and having a running joint with the rotatable parts therebetween, means coupling the impellers together and a spline on said shaft engaging one impeller hub and abut-

ting against the other impeller when the 40 runners are screwed together.

3. In a multi-stage centrifugal pump having high and low pressure impellers arranged back to back on a rotatable shaft, a casing having an inlet on one side and a 45 discharge outlet on the other side, a cover forming with said casing an intermediate passage, said casing and cover joined on a plane at right angles to said shaft and a diaphragm adapted to close an opening in 50 the casing of greater diameter than the impellers and interposed between the impellers and having a running joint with the rotatable parts therebetween, the impellers coupled by screw threads on their hubs con- 55 centric with said joint and a spline on said shaft engaging one impeller hub and abutting against the other impeller when the runners are screwed together.

4. In a multi-stage centrifugal pump having high and low pressure impellers arranged back to back on a rotatable shaft, a casing having an inlet on one side and a 60 discharge outlet on the other side, a cover forming with said casing an intermediate 65 passage, said casing and cover joined on a plane at right angles to said shaft and a diaphragm adapted to close an opening in the casing of greater diameter than the impellers and interposed between the impellers 70 and having a running joint with the rotatable parts therebetween, means coupling the impellers together concentric with said joint and a spline on said shaft engaging 75 one impeller hub and abutting against the other impeller when the runners are screwed together.

ALADAR HOLLANDER
